UNITED STATES PATENT OFFICE.

EDWARD HARDIS, OF PHOENIX, ARIZONA, ASSIGNOR TO EDWARD MERLE HARDIS.

CENTRIFUGAL PUMP.

1,207,546.

Specification of Letters Patent.

Patented Dec. 5, 1916.

Application filed August 26, 1915. Serial No. 47,524.

To all whom it may concern:

Be it known that I, EDWARD HARDIS, a citizen of the United States, residing at Phoenix, in the county of Maricopa and State of Arizona, have invented certain new and useful Improvements in Centrifugal Pumps; and I do declare the following to be a full, clear, and exact description of the invention, such as will enable others skilled in the art to which it appertains to make 10 and use the same.

My invention relates to centrifugal pumps of that type wherein a pump head is mounted for rotation within a chamber and tends to draw water to the center of the head from which point it is discharged centrifugally into the chamber.

An object of the present invention is to provide novel means for centering the rotating members within the chambers.

Another object is to provide means for centering said chambers within the well casing and for preventing their rotation.

A further object is to construct a pump head which can be cheaply manufactured yet one which will be extremely efficient in operation.

With the above and minor objects in view my invention consists of the novel features of construction, combination and arrangement of parts as will hereinafter be more fully described and claimed, as shown in the drawing wherein:

Figure 1 illustrates a central vertical section of a portion of the well casing showing a number of my improved pump heads mounted for rotation in their respective chambers, one of said chambers being shown in section; Fig. 2 is a horizontal section on line 2-2 of Fig. 1; Fig. 3 is an enlarged detail vertical longitudinal section through a portion of the well casing and the parts contained therein, and, Fig. 4 is a horizontal transverse section on the line 4-4 of Fig. 3.

In the accompanying drawings wherein similar reference characters designate corresponding parts throughout the several views, 1 indicates a well casing having formed therein a series of openings 2 at each stratum of water in the well, such casing being closed at its upper end by a suitable cap member 3 which is herein shown as having an inclined discharge pipe 4 formed 55 on its outer face.

This discharge or outlet pipe 4 has its up-

per portion provided with a suitable bearing 5 which is adapted to rotatably receive a shaft 6 which will be more particularly described hereafter. The outer edge of this pipe 4 is further provided with a flange 7 to which is bolted a discharge pipe 8 of smaller diameter than the first mentioned discharge pipe, said pipe 8 having both horizontal and vertical discharge openings either of which 65 may be used for conveying water raised from the well.

An opening 9 is formed through the well cap 3 preferably in its center and is surrounded by a flange 10 adapted to receive 70 therein the upper threaded end of the pipe 11 adapted to convey the water raised from the well to the discharge pipe 4. The free end of the pipe 11 is secured in an internally threaded sleeve 12 which is formed 75 integrally with the conical shaped top 13 of the pump head receiving chamber 14, the bottom of this chamber 14 being also provided with an integrally formed internally threaded sleeve 15 depending from its outer 80 face which is adapted to receive one end of an additional pipe 11'. This section of pipe 11' has its free end connected in the upper end of an additional casing or chamber similar 85 in all respects to the first mentioned chamber 14. These chambers 14 are disposed at suitable intervals throughout the length of the well casing, their number depending upon the depth of the well. The lowermost of these casings is preferably disposed beneath the normal level of the water 90 in the well, from which chamber said water is raised by suction to the next chamber and so on up to the top of the well casing. By disposing the lowermost chamber below the 95 normal level of the water, priming of the pump mechanism is not necessary before starting the operation thereof.

This pump mechanism comprises substantially a series of pump heads 16, one of 100 which is disposed in each of said chambers, and which are connected by sections of shafting 17 to one another. The uppermost pump head is connected by the shaft section 6 which passes through the bearing 5 and 105 has its outer end connected with any suitable source of power for rotating said shaft. This rotating means may be either a motor directly connected with said shaft or as shown in Fig. 1 the end of the shaft may be 110 keyed to a belt pulley 18.

As the chambers 14 and the pump heads

16 are all constructed in a manner similar to one another but one of each will be described. The chamber 14 is formed of two separable sections 19 and 20, the section 19 having its lower end offset to form a flange 21 which is internally threaded for the reception of the externally threaded upper end of the lower section 20. The section 19 has the conical shaped top 13 formed integrally with its upper edge, and as hereinbefore stated this top 13 is provided with the integral sleeve 12 which is adapted to receive the pipe sections 11 or 11'. The lower section 20 of this two-piece chamber has lugs 22 formed at intervals around its outer face, said lugs being adapted to receive the shank portions 23 of hook shaped leaf springs 24. The leaf springs 24 have their outwardly bowed portions 25 contacting with the surface of the well casing 1, while their free ends are bent to form the bills 26 which are adapted to underlie and bear against the bottom of the casing 14 as clearly shown in Fig. 3 of the drawings. These springs not only keep the chambers centered with respect to the casing 1, thereby maintaining the shafts 6 and 17 in vertical alinement, but they also tend to prevent rotation of the chambers 14 relative to the casing.

As hereinbefore stated the bottom of the section 20 of the chamber is provided with an internally threaded depending sleeve 15 which surrounds an opening 27 formed in said bottom and is adapted to receive one end of the pipe section 11'. This sleeve is also adapted to receive a pipe extension 28 which projects a short distance within the casing 14, and is adapted to project through a circular bearing opening 29 formed in the bottom of a disk-shaped pump head 16. This pipe extension 28 is preferably formed of bronze but it is obvious that it may be formed of any suitable metal or even of glass, and that it acts as a stub shaft for centering said pump head within the chamber 14, thereby maintaining the shafts used to rotate said pump head in vertical alinement.

50 The pump head 16 comprises substantially a pair of disk-like members 30 and 31 respectively, the member 31 having the bearing opening 29 formed therethrough. These members 30 and 31 are slightly concave with their outer edges close together and their centers farther apart to provide the cavity 32. The aforesaid members 30 and 31 are integrally connected by propellers 33, which are tangentially disposed relative to the opening 29 as clearly illustrated in Fig. 4 of the drawings. It is obvious that by providing an integral structure such as shown much greater strength is obtained than by providing separable members for composing the pump heads. The lower member 31 is

provided at diametrically opposite points on its lower face with wings 34, while the upper member 30 has an internally threaded sleeve 35 integrally formed therewith and extending upwardly. The sleeve 35 is adapted to receive the enlarged ends 36 of the shaft sections connecting the series of pump heads, said enlarged ends being locked in said threaded sleeve to prevent rotation thereof, in any suitable manner. As clearly shown in Fig. 3 the pump head 16 is connected to the rotating shafts only at its upper end.

In operating my improved centrifugal pump the source of power is connected to the outer end of the shaft 6 for rotating said shaft, which will cause the rotation of all the pump heads connected either directly or indirectly therewith. Each of these pump heads will rotate in the direction of the arrow, and each will suck the water from the head directly below through the pipe 11' and into the cavity 32 within said pump head, from which the water will be discharged between the disk-like sections 30 and 31 in the form of a thin horizontal sheet into the chamber 14. This operation will then be repeated, the water being guided by the inclined upper end of the chamber 14 into the pipe section 11' directly above. By providing a sufficient number of pump heads with a strong enough shaft connecting them, the water may be raised from very deep wells with comparative ease.

From the foregoing description taken in connection with the accompanying drawings it is obvious that I have provided a very simple yet extremely efficient device for carrying out the objects of the invention.

Although I have described only the elements best adapted to perform the functions of the device, it is obvious that various changes in the form, proportion and minor details of construction may be resorted to within the scope of the appended claims without departing from the principle or sacrificing any of the advantages of the invention.

Having described my invention what I claim as new is:

1. The combination with a well casing, of a pipe disposed within said casing, enlarged chambers formed at intervals in said pipe each of said chambers having a conical shaped top and a flat bottom with an opening therethrough, means for centering said chambers in the casing, a pipe extension projecting within said chamber, a pump head rotatable on said extension in each of said chambers, a shaft connecting said pump heads, and means for rotating said shaft.

2. The combination with a well casing, of chambers disposed at intervals throughout the length of said casing, each of said cham-

- bers being formed of upper and lower separable sections, pipe sections connecting the outer ends of said chambers, a pipe extension projecting within each of said chambers, means formed on the lower section of each of said chambers for centering the same, a pump head rotatable on each of said extensions, a shaft connecting said pump heads, and means for rotating said shaft.
3. The combination with a well casing, of chambers disposed at intervals throughout the length of said casing, each of said chambers being formed in two separable sections, the upper section having a conical shaped top with a threaded sleeve extending from its apex, the lower section having a threaded sleeve depending from its bottom, pipe sections connecting said sleeves, a pipe extension projecting into each of said chambers, means formed in the lower section of each of said chambers for centering the same, a pump head rotatable on each of said extensions, a shaft connecting said pump heads, and means for rotating said shaft.
4. The combination with a well casing, chambers disposed at intervals throughout the length of said casing, pipe sections connecting the outer ends of said chambers, lugs formed on the outer sides of said chambers adjacent their bottoms, hook-shaped springs secured by their shanks in said lugs, their outwardly bowed portions contacting with
- the well casing and having their free ends underlying the bottoms of said chambers and contacting therewith, the free end portions of said springs sliding beneath said chambers when the same move toward the well casing, a pump head rotatable in each of said casings, a shaft connecting said pump heads, and means for rotating said shaft.
5. The combination with a well casing, of two piece separable chambers disposed at intervals throughout the length thereof, pipe sections connecting the ends of said chambers, spring means for centering said chambers in said casing, a pipe extension projecting within each of said chambers, a disk shaped pump head disposed for rotation in each of said chambers, a circular bearing opening in the bottom of each of said heads and adapted to receive said pipe extensions, a threaded sleeve formed integrally with the top of each of said heads, a shaft connecting said pump heads and having its ends threaded into said sleeve, and means for rotating said shaft.

In testimony whereof I have hereunto set my hand in presence of two subscribing witnesses.

EDWARD HARDIS.
